(57) **CLAIM**

The ornamental design for a mini portable file organizer, as shown and described.

DESCRIPTION

FIG. 1 is a left elevation view of my invention showing my new design;

FIG. 2 is a right elevation view of my invention showing my new design;

FIG. 3 is a front elevation view of my invention;

FIG. 4 is a rear elevation view of my invention;

FIG. 5 is a top view of my invention showing my new design;

FIG. 6 is a bottom view of the invention;

FIG. 7 is a perspective view of my invention showing my new design; and,

FIG. 8 is a perspective view of my invention in the open position showing my new design.

1 Claim, 5 Drawing Sheets

FIG. 1

FIG. 2

FIG. 3

FIG. 4

FIG. 6

FIG. 5

FIG. 7

FIG. 8
